INTERNAL-COMBUSTION ENGINE

Henry Ford, Dearborn, and Charles E. Sorensen,
Detroit, Mich., assignors to Ford Motor Company,
Dearborn, Mich., a corporation of Delaware

Application April 20, 1942, Serial No. 439,632

1 Claim. (Cl. 123—90)

This invention relates to internal-combustion engines and more particularly to a drive for camshafts in such engines.

At the present time in the design of internal-combustion engines of large horsepower, notably aviation engines, provision is frequently made for separate activation of the exhaust and intake valves by individual camshafts. This system has certain advantages as, for instance, when two or more intake or exhaust valves are provided for each cylinder their operation by a single cam-shaft would be complicated and cumbersome. There are other circumstances in which the use of individual camshafts is advantageous; but since the invention principally concerns the camshaft drive, they need not be listed here.

In the devices of the prior art, whether single or multiple overhead camshafts were used to operate the intake and exhaust valves, the camshafts were driven by gearing from the motor crankshaft. When multiple camshafts were used, this generally took the form of a bevel gear train from the crankshaft to one of the camshafts and a further gearing from the driven camshaft to the other camshaft. Apart from the excessive weight and the inherently larger size of a bevel gear system, difficulty was encountered in providing suitable bearings. And since the system used a multiplicity of gears, the over-all efficiency was necessarily low.

In addition to these difficulties, provision must be made on these engines to run a number of auxiliaries such as magnetos, injectors, and pumps in exact synchronization or in some fixed speed ratio with the motor. The preferred position for attaching these auxiliaries is in proximity to the driven end of the camshafts. The reason for this is that the camshaft is in synchronization with the motor; and being located at the top of the motor is readily accessible for such attachments. The driven end of the camshaft is preferred because it avoids defects in synchronization caused by whip in the shaft. When the camshafts are driven as shown in this invention, the driven end of each camshaft is available for the attachment of auxiliaries, a feature which does not appear in any other motor, to the applicants' knowledge.

A further reference to the prior construction will make this point clear. In the usual construction, bevel gears are attached to corresponding ends of the crankshaft and camshaft. A drive shaft having bevel gears at each end is arranged between the crankshaft and camshaft, its gears meshing with those on the last-named shafts. It follows that the drive shaft must be positioned

a distance, equal to at least one half the major diameter of the bevel gear used, beyond the normal support for the crankshaft or camshaft. The auxiliaries used are generally of such size that they must be placed beyond the bevel gears on the drive shaft to clear them. This requires that the camshaft be extended a distance, equal to at least the major diameter of the bevel gear, to make operating connection with the auxiliary. This is a substantial distance; and some provision for additional bearing for the shaft overhang, as well as a support for the auxiliary must be made—a far from simple problem.

When pairs of camshafts are used, but one of them may be driven directly from the bevel drive. The other camshaft is then driven by the first camshaft usually through conventional spur gearing. This involves a further gear train with consequent greater weight, chance for mistiming, and a more complicated construction.

Another difficulty encountered when a bevel drive is used is in balancing the forces imposed on the drive shaft. As there is engagement on but one side thereof by the meshing gear of the camshaft, any thrust must be taken care of by suitable bearings.

The present invention overcomes each of these disadvantages. With the use of a worm gear system, the gear on the crankshaft, the drive shafts, and the gears on the camshafts are all substantially in one plane. The saving in space is at once apparent. The worm on the drive shaft is preferably placed between wheels on the two camshafts directly engaging with both of them, no further gearing being required between the two camshafts. As both are driven by the same worm, there is no opportunity for mistiming.

Since the drive and driven gears are in the same plane, no difficulty is encountered in providing adequate bearings for the end of the camshaft as shown in Figure 3; and auxiliaries of whatever size desired can be attached to the end of a camshaft without an undue extension of the camshaft. Again, since the gearing does not cover the end of any camshaft, all the camshafts are available for the attachment of auxiliaries. A final advantage is that by engaging each camshaft from opposite sides of the worm, the opposing forces on the worm therefrom are balanced. Compared to the older system where one camshaft was driven by the worm and in turn drove the other, the tooth strength of the worm gear on the drive shaft need be but half as great, as the impressed force is directly divided between the two camshafts.

With this and other objects in view, our inven-

tion consists of the arrangement, construction and combination of the various parts of our improved device, as described in this specification, claimed in our claim and illustrated in the accompanying drawings in which:

Figure 1 is a transverse vertical section of an engine employing the invention.

Figure 2 is a partial sectional view taken on the line 2—2 of Figure 1.

Figure 3 is a partial section on an enlarged scale taken on the line 3—3 of Figure 1.

Figure 4 is a partial transverse vertical section on an enlarged scale showing the upper end construction.

Figure 5 is a diagrammatic view showing the 15 spline relationship.

Referring to Figure 1, 10 indicates a V-type engine having the cylinder banks 11 with the usual pistons 21 connected by the rods 12 to the crankshaft 13. Overhead valve assemblies 14 are provided on top of the banks for each cylinder and are operated by the cams 15 on the camshafts 16. This general construction is well-known in the art and presents no novelty.

Separately spaced camshafts 16 are provided for the intake and for the exhaust valves in each bank of cylinders. The intake valves, in the embodiment shown, are those located toward the interior of the V, and these are operated by the inner camshaft while exhaust valves adjacent the outer side of the bank are operated by the other camshaft. Instead of conventional manifolding, the space 17 within the V serves as the intake manifold and an intercooler 18 is shown secured between the V for use with a supercharger to cool the entering air. The block casting is reinforced at its lower edge by cored box 19 which follows around the entire periphery of the block and adds the necessary rigidity. To it is attached the usual crankcase 20.

This invention is particularly directed to the means for driving the camshafts from the crankshaft and the method used in assembling this structure. As shown, a worm wheel 22 is secured to an extension 23 on the crankshaft 13 (see Figure 2) and meshes with the two worms 24, shown here to be of the hour-glass or globoid type, which are secured to the drive shaft 25. This drive shaft is rotatably mounted at the lower end of the bearings 26 and at its upper end in a bearing 27 at the top of the block 28 adjacent to the division line between the block and head casting 29. The quill 30 is splined to the drive shaft 25 and extends upwardly where, as best seen in Figure 4, it is splined to the upper worm 32. This worm, in turn, meshes with the two upper worm wheels 33, which are splined to the extension 34 of the camshaft 16.

In the present instance, a helix angle of approximately 45 degrees is used in designing the worm gearing; and the speed ratio between the crankshaft and the camshaft is 2:1. Other angles and ratios may be chosen as are required for the individual design, but those skilled in the art will recognize that in the interest of efficiency, a helix angle approaching 45 degrees should be used.

Referring to Figure 2, it will also be noted that another gear 35 is mounted on the crankshaft extension 23 and meshes with the pinion 36 splined to the shaft 37, extending rearwardly of the motor which serves as an additional accessory drive.

As best seen in Figure 3, a splined connection 38 is available at the end of each camshaft

extension 34 which, together with the facing plates 39, for the ready attachment and drive of such devices as timing gear, injection pump, magneto or other equipment which must be driven in exact synchronism with the motor. Further, as the lower worm is supported by bearings both above and below its point of engagement with the worm wheel and the upper worm is supported between two worm wheels, the side thrust ordinarily found in such constructions is obviated. In addition, the over-all length of the camshaft is reduced and the rigidity of attachment of accessories increased.

An extension of the invention is to be found in the method used for the assembly of the components. It is absolutely necessary that the phase angle of the camshaft be correct within 1 degree of the corresponding phase position of the crankshaft. The use of the worm at each 20 end and the fact that the upper worm meshes with two camshafts particularly complicate the process of assembly. In order to permit exact synchronism of the crank and camshafts, the quill 30 is provided with a differential number 25 of splines at top and bottom. Thus, in this construction, the top splines 40 are 22 in number while the bottom splines 42 are 38 in number. Of course, the splines that co-operate with these, namely those in the upper worm 32 and the top 30 of the drive shaft 25, respectively, are correspondingly similar in number. Employing the Vernier characteristics of this differential spline, the possible number of different positions numbers 209, and as the crankshaft may be rotated 35 180 degrees in either direction, the actual positions number 418 in which an adjustment may be made. The proper synchronism of the crankshaft and camshaft may thus be kept well within the one-degree limit.

In practice, the two camshafts are adjusted to the desired phase angle, the upper worm wheel 33 engaged with the upper worm 32, and the assembly is locked and marked as shown at 43 to indicate alignment. It will be noted that the 45 upper worm 32 is supported in the upper bearing 44 and the lower bearing 45 so that it maintains itself in position during this step. The crankshaft is turned to its approximate angular location within the one-degree limit, which accordingly moves the drive shaft 25 to a certain position. The quill 30 is then dropped down through the upper worm 32 and its upper splines 40 mesh with the corresponding splines on the upper worm. Unless the alignment is exact, however, the lower splines 42 will not mesh with corresponding splines in the drive shaft 25. Accordingly, the quill is lifted upwardly until the 50 spline 40 is disengaged and is reinserted in another angular position. This is continued until all of the tooth combinations have been exhausted or until a position is found in which the quill readily engages the splines in both the worm and the drive shafts. In the event that 55 this matching is not obtained while the quill is moved from each tooth successively through 180 degrees, the crankshaft is rocked slightly within the indicated limit and the procedure repeated. In this way, at least one condition will be found in which the teeth at both ends of the quill mesh perfectly with the splines in the worm and drive shaft, respectively. When this is obtained the timing is correct with respect to the crank position within the very narrow limits 60 which have been set. This permits a very close

adjustment and one which is well-adapted to the assembly of this type of engine.

The advantages of this construction are manifold. The device is more compact and lighter than other conventional drives. It leaves the ends of all camshafts available to drive auxiliaries, and provides a secure and rigid base for the attachment of these auxiliaries. The drive to each pair of camshafts is direct, and as the drive shaft is positioned between the camshaft in the pair, the thrust forces are largely balanced. End bearings are provided for the cam-shaft, crankshaft and drive shaft and overhanging shafts avoided. A wide range of speed ratios is available without an undue increase in the size of the gear and, particularly when the hour-glass or globoid worm is used, the efficiency is extremely high.

Some changes may be made in the arrangement, construction, and combination of the various parts of the improved device without departing from the spirit of the invention. It is the intention to cover by the claims such changes as may be reasonably included within the scope thereof.

We claim as our invention:

In combination, in an internal-combustion engine of the V type, a camshaft drive, comprising, a pair of overhead camshafts rotatably mounted on each cylinder bank of said engine, a worm wheel disposed at one end of each camshaft, a main shaft having a worm wheel disposed at its corresponding end, a pair of intermediate shafts having worm gears disposed at each end thereof, means on said bank providing a cam-shaft bearing on each side of said worm wheel thereon and a facing plate in proximity thereto, said intermediate shafts being so arranged that the lower worm gears thereon mesh with said main shaft worm wheel on opposite sides thereof, and extending therefrom divergently to said cam-shaft pairs, the upper worm gears thereon each disposed between and meshing with one of said worm wheel pairs, providing a drive means between said main shaft and said camshafts without obstruction at the ends of said camshafts permitting the attachment of auxiliaries thereto, said camshaft drive being substantially in one plane.
